VALVE MECHANISM FOR SPAGHETTI
CANNING MACHINESGeorge M. Gillen, Paterson, N. J., assignor to
Nicholas Pisapia, Paterson, N. J.

Application January 18, 1944, Serial No. 518,763

4 Claims. (Cl. 222—332)

This invention relates to canning machinery, and is more particularly concerned with a measuring valve device for use in connection with the canning of spaghetti or like material.

In canning machinery it is conventional to provide a source of the material to be canned and a conduit leading from that source to a discharge nozzle which is fitted in or over the container to be filled. In the conduit connecting the source with the discharge nozzle it is customary to provide a measuring device or valve which is intermittently operated to dispense to the nozzle successive measured quantities of the material to be canned, each dispensing operation involving enough of said material to fill an individual can, jar or the like. Thus, the empty cans are successively placed in registry with the nozzle and are successively accurately filled as the measuring valve completes an operating cycle.

Of course, measuring valves of the general type mentioned above are at present well known and they conform to a wide variety of shapes adapted for various conditions of operation. It has been found, however, that in the canning of spaghetti or like material, peculiar problems are presented which render conventional canning machinery unsatisfactory. This difficulty arises largely because of the nature of spaghetti itself. Cooked spaghetti, when fed in bulk to a measuring valve, forms a continuous more or less air-locked column of such a nature that it is impossible to vent the measuring valve through the material, as is often done in the case of granular substances. Neither can an ordinary air vent be used because of the fact that spaghetti is made up of elongated components which, in cooked condition, will quickly clog an air vent of conventional form.

Furthermore, because of the fact that cooked spaghetti packs together to form a continuous body, there is a tendency to jam the valve as it moves from filling to dispensing position, thereby resulting in defective operation either from the point of view of timing or the amount of material dispensed.

It is, therefore, an object of this invention to provide a measuring valve device particularly adapted for use in machines for canning spaghetti or the like, which valve is adequately vented during both the filling and discharge operations, and which is designed to sever the column of material upon movement away from the filling position in such a manner as to assure the filling of the chamber of the measuring valve and the rapid and clean severance of the remainder of the material from the measured amount.

It is contemplated, according to this invention, that a self-cleansing air vent be provided in the measuring valve of a spaghetti filling machine, so that continued operation over long periods of time is possible without loss in efficiency.

Other objects and advantages of this invention will be apparent from a detailed consideration of the following description of a preferred embodiment thereof in conjunction with the annexed drawings, wherein:

Figure 1 is a view in side elevation of a preferred form of this invention, illustrating in broken lines a portion of the support for the measuring valve;

Figure 2 is a front view of the measuring valve device partially in vertical section better to illustrate the structure of the rotating element;

Figure 3 is a view in section taken on line 3—3 of Figure 2; and

Figure 4 is a top plan view of the rotary element of the valve removed from the assembly for convenience in illustration.

Referring now to the drawings in greater detail, it will be seen that the valve device is made up of a frusto-conical hopper 10, a measuring valve assembly 11 and a discharge nozzle or fitting 12. Valve assembly 11 is provided with a support 13 which is mounted on a base 14, resting in turn on a bench or platform 15 conveniently disposed within the cannery. Frusto-conical hopper 10 may be conveniently made of sheet metal with its small open end welded or otherwise attached to a rectangular plate 16 provided with a round centrally located opening equal in size to and registering with the discharge opening of the hopper. Plate 16 rests upon and is affixed by bolts 17 to an exteriorly flattened upper portion of an interiorly cylindrical valve housing 18, said housing having an aperture at 19 of an interiorly cylindrical valve housing in its upper wall registering with that in plate 16 and serving with it to establish communication between the hopper 10 and the interior of the valve housing 18.

Valve housing 18 consists of a hollow casting open at one end and there provided with a cover plate 20 attached by bolts 21, see Figure 1. The bottom of valve housing 18 is provided with an integral flattened lower portion 22 in all respects similar to the corresponding upper portion to which plate 16 is bolted. Portion 22 is provided with a round central opening at 23 leading to the hollow interior of housing 18. The openings at 19 and 23 are disposed on a vertical axis 180° apart. Nozzle 12 is attached by bolts 24 to the flattened lower portion 22 of valve housing 18,

being provided with a flange in the form of a rectangular plate 25 for this purpose.

The integral end wall of valve housing 18 is provided with a bearing sleeve 26 for the reception of a hollow stub shaft 27 extending from one end of cylindrical rotary valve element 28 which is disposed within the cylindrical interior of valve housing 18. Cover plate 20 of valve housing 18 is provided with a similar bearing sleeve 29 for the reception of stub shaft 30 extending from the other end of valve element 28. The valve element is, therefore, mounted for rotation within valve housing 18, turning on its two concentric stub shafts 27 and 30.

The portion of valve housing 18 to the rear of the operator is also exteriorly flattened and is provided with interiorly threaded sockets for the reception of bolts 31 which fasten the valve housing to support 13. Support 13 consists of an arm 32 extending outwardly from a vertical rod 33. Rod 33 is threaded at its base and may therefore be raised or lowered with respect to block 14, thereby raising or lowering the valve assembly with respect to platform 15, so that containers of different heights may be readily accommodated under nozzle 12. In this connection see Figure 1.

As has been stated before, valve housing 18 is interiorly cylindrical and is provided with an intake port at 19 and a discharge port at 23. Ports 19 and 23 are in vertical alignment and lie directly under the vertical axis of frusto-conical hopper 10. If, therefore, frusto-conical hopper 10 were filled with a material, and if rotary valve element 28 were not provided, the material would fall vertically through valve housing 18 in a straight line. Of course, it is necessary to direct the material into the container. For this reason the frusto-conical filler nozzle 12 is provided, the base of which is welded to flange plate 25.

Valve element 28 is both interiorly and exteriorly cylindrical. Its external diameter is such that it fits closely within valve housing 18. Projections 34 on the end walls of valve element 34 rest against the corresponding end walls of valve housing 18 and hold valve element 28 against axial displacement. As can be seen upon reference to Figure 4, valve element 28 is provided with an aperture at 35 in its cylindrical wall, said aperture being of a size and in position to exactly register with either of the apertures at 19 and 23 in valve housing 18. It is now evident that with valve element 28 in the position shown in Figure 2, material from hopper 10 will tend, by gravity flow, to fill the valve element and then to cease flowing. If the valve element is then turned 180° its aperture 35 will be displaced from registry with aperture 19 to registry with aperture 23, at which time discharge of the contents of valve element 28 will take place through frusto-conical nozzle 12.

In using a device of the character shown in Figure 2 with a material such as cooked spaghetti, two very serious difficulties arise, which difficulties are overcome by the present invention, rendering it particularly suitable for use in the canning of spaghetti and like materials. In the first place, when hopper 10 discharges into valve element 28 a continuous body of material extends from the hopper through aperture 35 and into the valve element. In view of the elongated character of spaghetti, it is essential that the edges of valve element 28 which defines the aperture at 35 be sufficiently sharp so that when the valve

is turned a cutting action will take place, thus severing the continuous strands of spaghetti and subdividing the pre-existing continuous body into a body still within hopper 10, and another body enclosed within valve element 28. Upon reference to Figure 2 it will be seen that the material of which valve element 28 is made is thick but is beveled adjacent aperture 35, so that the actual defining edge of that aperture is thin and sharp, resulting in the cutting action previously described.

In view of the fact that cooked spaghetti forms a continuous and compact body, it is insufficiently foraminous to permit the ready escape therethrough of the air which is displaced from valve element 28 during filling of its hollow interior. This being the case, filling would be considerably retarded were it not for the novel and convenient air vent provided in accordance with this invention. Upon reference to Figure 2 it can be seen that shaft 27 is hollow, defining a central conduit. This conduit is continued through end plate 36 of valve element 28 and terminates in a disk-shaped recess 37 on the interior wall of plate 36. By this arrangement a continuous air vent is provided from the interior of valve element 28 to the end of shaft 27. A suitable packing joint is held in place by flanged sleeve 38 and, from this joint, a stationary vent pipe 39 extends to the top of hopper 10, being supported from hopper 10 by a bracket 40. Note that bearing sleeve 26 of valve housing 18 extends beyond the end of hollow stub shaft 27 so that the rotation of the latter does not interfere with the packing joint. This joint is made up of an external flange or the end of pipe 39 and the end of bearing sleeve 26 an annular washer being disposed therebetween and held under compression by threaded flanged sleeve 38.

It has been found that due to the nature of cooked spaghetti, a bore such as that provided in end plate 36 and stub shaft 27 soon becomes clogged with spaghetti and thereby prevents the very venting action which is sought. This being the case, recess 37 is fitted with a screen 41 which is held in position against the bottom of the recess by an annular washer 42, in turn held by bolts 42a with its face flush with the end plate 36. Washer 42 prevents the spaghetti from packing tightly against the screen 41. This screen is of a mesh fine enough to prevent the spaghetti from bodily entering the vent and is of sufficient area to act as a continuous wall for the spaghetti material when the latter is in the measuring valve element 28. Of course, the vent acts to supply air to valve element 28 during discharge, as well as for the accommodating displaced air during filling.

It has been explained that valve element 28 is rotated 180° from the filling to the discharge positions. According to this invention such action is effected automatically. To this end a drive gear 43 is keyed to the end of stub shaft 30 and is in a position to mesh with another gear 44, the driving teeth of which are interrupted in two zones 180° apart. When the interrupted zones register with the teeth of gear 43, the latter is momentarily not driven and consequently stops. The angular adjustment of the two gears 43 and 44 is such that the interrupted portions of the latter will register with the teeth of the former when aperture 35 of valve element 28 is in registry with first aperture 19 and then aperture 23 in repeated sequence. Gear 44 is continuously driven through a shaft 45 from a source, not shown, at a speed

such that movement through the interrupted zone of the teeth will be sufficient to permit either filling or discharge, depending upon the particular station in which valve element 28 finds itself upon cessation of motion.

Although in the specification and the accompanying drawings there is shown and described a preferred embodiment of this invention and various modifications thereof, and although various alternatives are suggested, these are not intended to be exhaustive or limiting of the invention, but, on the contrary are given for the purpose of illustrating it and instructing others in the principles thereof as well as the best practical manner of utilizing the invention in order that others may be enabled to modify it and apply it in numerous forms each as may be best suited to conditions and requirements in any particular instance.

What is claimed is:

1. A device for dispensing measured amounts of spaghetti or the like comprising a vertically extending conduit for supplying material from a source to a point of discharge, an interiorly cylindrical valve housing in said conduit, an exteriorly cylindrical hollow valve element, means mounting said valve element in said housing for rotation on a horizontal axis, said valve element having an aperture in its cylindrical wall in position to register with the conduit above and below it, and a port centrally located in its end wall, said mounting means having a vent continuously in open communication with said port and the atmosphere, a screen disposed in spaced relation to the end wall of said valve element and covering said port, and means for periodically angularly displacing said valve element in repeated cycles 180° from a position in which its aperture is in registry with the portion of the conduit thereabove to a position in which its aperture is in registry with the conduit therebelow.

2. A dispensing device as claimed in claim 1 in which said valve element has an annular recess surrounding said port, said screen mounted in said recess, and an annular washer for holding said screen against the bottom of said recess, said washer lying flush with the wall of the valve element.

3. A device for dispensing measured amounts of spaghetti or the like comprising, a vertically extending hopper, a discharge nozzle, a vertically

- extending conduit connecting said hopper and said discharge nozzle, an interiorly cylindrical valve housing in said conduit, an exteriorly cylindrical hollow valve element in said valve housing, said valve element having an aperture in its cylindrical wall in a position to register with the portion of the conduit thereabove and therebelow, and a port centrally located in its end wall, the end wall of said valve element being annularly recessed about said port, a screen in said recess covering said port, said mounting means having a vent continuously in open communication with said port and the atmosphere, a tubular conduit connecting said vent passageway to atmosphere, said tubular conduit extending to a point adjacent the top of said hopper, and means for periodically angularly displacing said valve element in repeated cycles of 180° from a position with its aperture in registry with the portion of the conduit thereabove to a position with its aperture in registry with the portion of the conduit therebelow.
4. A device for dispensing measured amounts of spaghetti or the like comprising a vertically extending conduit for supplying material from a source to a point of discharge, an interiorly cylindrical valve housing in said conduit, an exteriorly cylindrical hollow valve element, means mounting said valve element in said housing for rotation on a horizontal axis, said valve element having an aperture in its cylindrical wall in position to register with the conduit above and below it, and a port centrally located in its end wall, said mounting means having a vent continuously in open communication with said port and the atmosphere, a screen disposed against the end wall of said valve element and covering said port, and means for periodically angularly displacing said valve element in repeated cycles 180° from a position in which its aperture is in registry with the portion of the conduit thereabove to a position in which its aperture is in registry with the conduit therebelow, said valve element having relatively thick walls beveled to thinness at the area surrounding said aperture, whereby a continuous column of spaghetti in the conduit above the valve element will be cut off and distributed within the valve element as the latter moves away from filling position.
